UNITED STATES PATENT OFFICE

HARRY H. GERJETS, OF BELLINGHAM, WASHINGTON

CIGARETTE RECEPTACLE AND ROLLER

Application filed April 7, 1932. Serial No. 603,881.

This invention appertains to new and useful improvements in special receptacles, and more particularly to a novel cigarette case which involves means whereby cigarettes can be easily rolled and conveniently stored.

The principal object of the invention is to provide a combination cigarette case and roller wherein cigarettes can be rolled and stored plus stock stored.

Other important objects of the invention will become apparent to the reader of the following specification.

In the drawings:—

15 Figure 1 represents a perspective view of the device closed.

Fig. 2 represents a perspective view of the device opened.

20 Fig. 3 represents a top plan view of the device stripped for use in rolling cigarettes.

Fig. 4 represents a longitudinal sectional view through the device as shown in Fig. 3.

25 Fig. 5 represents a transverse sectional view taken substantially on line 5—5 of Fig. 4.

Fig. 6 represents a perspective view of the slider.

30 Fig. 7 represents a fragmentary top plan view of the rolling device with the slider removed.

Referring to the drawings wherein like numerals designate like parts, it can be seen that numeral 5 represents the cover section while numeral 6 generally refers to the rolled cigarette support and rolling device.

This combination device 6 includes a plate 7 which is provided with a pair of side walls 8—8 (see Fig. 5), each having its edge portion turned inwardly as at 9 to terminate in spaced 40 relation from the plate 7 to define a guideway 10 in which the side walls 11—11 of the slider generally referred to by numeral 12 can engage and freely slide longitudinally of the plate 7. The slider 12 is provided with a platform 13 connecting the upper edges of the side walls 11—11, and as is clearly shown in Fig. 6, one end portion of the platform 11 is disposed downwardly as at 14 and extended as at 15 in this lowered position to the adjacent end of the slider where it extends up-

wardly to form the flange 16. The upper edge of this flange 16 is bent inwardly as at 17 and between this edge portion 17 and the flange 16, one end of the cigarette rolling web 18 can be clamped. The other end of the platform 13 is bent under itself to provide a clamping flange whereby the opposite edge 55 of the web 18 can be secured to this last-mentioned edge of this platform 13.

The portion of the platform 13 adjacent the flange 16 thus formed provides a pocket 19. A roll 20 is disposed between the inturned edge portions of the side walls 8—8 on the plate 7, and this roll is located under the web 18. The web 18 sags into the pocket 19 and in this manner shown clearly in Fig. 4.

The operation of this device is as follows: The slider is first set so that the flange 16 is next to the roll 18. Then the web is depressed into the pocket 19 and a quantity of tobacco only, placed in this pocket. Now move the slider in direction indicated by the arrow 60 rolling the tobacco into a compact roll up on the raised platform 13. Then place a 65 moistened gummed paper on the web with the gummed side of paper up and the other edge nearest the roll 18 and move the slider the balance of the way indicated by the arrow. This will draw the paper around the 70 roll of tobacco completing the cigarette. 75

Sliding the slider back will eject cigarette into the lid which makes a convenient tray for quite a number of cigarettes while rolling.

80 While the foregoing specification sets forth the invention in specific terms, it is to be understood that numerous changes in the shape, size and materials may be resorted to without departing from the spirit and scope 85 of the invention as claimed hereinafter.

Having thus described my invention, what I claim as new is:—

1. In combination, a cigarette case, said cigarette case being in sections, one section 90 being a cover, the other section being provided with a slideway, a traveling web in the slideway, a transverse structure on the last-mentioned section over which the web travels, and a pocket on one side of the trans- 95 100

verse member into which the web extends, and in which and upon which web a cigarette paper and tobacco can be placed.

2. In combination, a cigarette case, said cigarette case being in sections, one section being a cover, the other section being provided with a slideway, a traveling web in the slideway, a transverse structure on the last-mentioned section over which the web travels, 10 a pocket on one side of the transverse member into which the web extends, and in which and upon which web a cigarette paper and tobacco can be placed, said last-mentioned section being provided with side walls extending upwardly beyond the web and between which finished cigarettes can be stored.

3. A cigarette rolling device comprising a plate having side walls bent downwardly to provide guides, a cross member between the side walls, a slider movable in the guideways, and a cigarette rolling web carried by the said slider and being disposed over the cross member.

In testimony whereof I affix my signature.

HARRY H. GERJETS.
